UNITED STATES PATENT OFFICE.

LEWIS DETAR AND LEWIS D. MUNSHOWER, OF SHELOCTA, PENNSYLVANIA.

SCREENING-MACHINE.

SPECIFICATION forming part of Letters Patent No. 462,810, dated November 10, 1891.

Application filed June 4, 1891. Serial No. 395,090. (No model.)

To all whom it may concern:

Be it known that we, LEWIS DETAR and LEWIS D. MUNSHOWER, citizens of the United States, residing at Shelocta, in the county of Indiana, State of Pennsylvania, have invented 5 certain new and useful Improvements in Screening-Machines, of which the following is a specification, reference being had therein to the accompanying drawings.

10 This invention relates to certain new and useful improvements in screening-machines; and it has for its objects among others to provide an improved machine, by which the wheat will be thoroughly cleaned, novel means being provided for operating the various parts. 15 We provide an oscillating feed-bar connected with and operated by the shaft which actuates the riddles. We provide an adjustable connection between the crank-disk on said shaft and the feed-bar. The upper riddle is 20 made removable, so that it may be taken out during certain operations of the machine.

25 Other objects and advantages of the invention will hereinafter appear, and the novel features thereof will be specifically defined by the appended claims.

30 The invention is clearly illustrated in the accompanying drawings, which, with the letters of reference marked thereon, form a part of this specification, and in which—

35 Figure 1 is a vertical longitudinal section through our improved screening-machine, the section being taken on the line $z z$ of Fig. 2. Fig. 2 is a top plan with portions broken away.

Like letters of reference indicate like parts 40 in both views where they occur.

Referring now to the details of the drawings by letter, A designates the frame supported upon suitable supports, as the legs a , and at one end extended upward, as shown in Fig. 1, and at this end is provided the feed-hopper B, within which at the rear side is arranged an inclined shelf b , as seen in Fig. 1, and C is the feed-bar, journaled in the end walls of the hopper, the said feed-bar being cut away upon one side to substantially the center thereof, as seen in both views, and at one end extended beyond the end wall, as seen in Fig. 2, and provided with a crank-arm c , to the crank-pin c' of which is attached the pitman D D', adjustable in length, said adjustment being obtained in any suitable man-

ner—such, for instance, as by slot and set-screw, as shown in both views. The forward end of the arm D' is connected with the crank-pin d on the crank-disk E, carried by the cross-shaft E', which is journaled in suitable boxes or bearings on the upper edges of the side walls of the frame, as shown in Fig. 2. The other end of this shaft is provided with 55 suitable means by which it may be revolved. We have shown a crank-handle E².

Arranged within the box or casing formed by the frame is an inclined ledge or shelf e , beneath the feed-bar, as seen in Fig. 1, and 60 which serves to guide the material fed through the feed-opening into the upper riddle, as will be understood from Fig. 1.

F is the riddle-frame. It is suspended within the box or case by means of the hang- 65 ers or straps F', which are attached to the side walls of the box or case, as seen best in Fig. 1, and to the bottom of this frame is secured the reticulated medium F², which is of three or more different degrees of fineness of 70 mesh, the finest being toward the rear end of the machine. At the forward end, beneath this reticulated medium, is arranged an inwardly-extending plate G, as seen in Fig. 1, which serves to guide the material out through 75 the discharge-opening G' in the end of the box or case.

The riddle-frame is provided with longitudinal guides f upon the inner faces of its side walls, and upon these guides is designed to 80 be removably supported the frame H, the bottom of which is covered with reticulated medium H' of different degrees of mesh, finer than that of the lower riddle, the finest being at the rear end of the machine, the hooper 85 end being considered the rear end. This frame H is designed to be held in position by a removable pin or pins g , which pass vertically through one of the side bars of the riddle-frame and into the side bar of the frame 90 H. The removal of this pin permits of the ready endwise removal of the frame H. The riddle-frame F is yieldingly held to the case or box by the springs I, the tendency of which is to hold the frame toward the front end of 95 the machine, but which yield to permit of its movement in the opposite direction when actuated by the mechanism now to be described. Across the top of the said frame, at 100

a point beneath the cross-shaft E', is secured a bar I', to the upper face of which is secured a block J, the upper face of which is cam-shaped, as seen in Fig. 1, and upon the cross-shaft, at a point above the said block, is secured the cam K, provided with two or more cams k, which ride over the said block in the revolution of the shaft, as will be hereinafter more fully set forth. The bottom of the box 10 or case is inclined from opposite sides toward the longitudinal center, where a longitudinal opening l is provided, and L are adjustable dividers, the opposite transverse sides of which are inclined in opposite directions, as 15 shown in Fig. 2 and in section in Fig. 1, being substantially diamond-shaped, as seen best from Fig. 2. These dividers are adjustable along the slot or opening l, as indicated in Fig. 1, being held in their adjusted positions 20 by the spring-actuated plate M, which is designed to be forced against the under side of the bottom of the case by the spring m, confined between the said plate and a stop n on the stem o, which is secured to the piece O, 25 held between the sides of the divider, as shown in Fig. 1. When it is desired to adjust the divider, all that is necessary to do is to press upward upon the shank against the force of the spring and move the separator to the desired location, when the spring will force it 30 firmly and hold it in position.

The operation will be readily understood from the foregoing description when taken in connection with the annexed drawings. The

upper riddle is designed for cleaning clover, 35 timothy, and the like, and the under one for cleaning wheat. When cleaning wheat, the top riddle should be removed.

Various modifications in detail may be resorted to without departing from the spirit of 40 the invention or sacrificing any of its advantages.

What we claim as new is—

1. The combination, with the oscillating riddle-frame and the oscillating feed-bar, of 45 the riddle-operating shaft and cam-disk having a plurality of cams, and the pitman D D', adjustable in length, as set forth.

2. The combination, with the case having longitudinal slot in its bottom, of the riddles 50 one of which is removable and the spring-held adjustable dividers having oppositely-inclined transverse sides, substantially as specified.

3. The combination, with the case having 55 longitudinal slot in its bottom, of the dividers, the stem connected therewith, the plate designed to engage the under side of the case, the stop on the stem, and the spring arranged between said stop and plate, substantially as 60 and for the purpose specified.

In testimony whereof we affix our signature in presence of two witnesses.

LEWIS DETAR.

LEWIS D. MUNSHOWER.
